(57) **CLAIM**

The ornamental design for a telescoping handle, as shown and described.

DESCRIPTION

FIG. 1 is a perspective view of an extended handle showing our new design;

FIG. 2 is a right side view thereof;

FIG. 3 is left side view thereof;

FIG. 4 is a top view thereof;

FIG. 5 is a bottom view thereof;

FIG. 6 is a rear view thereof; and

FIG. 7 is a front view thereof.

FIG. 8 is a perspective view of a collapsed handle showing our new design and having the fork tines extended;

FIG. 9 is a right side view thereof;

FIG. 10 is left side view thereof;

FIG. 11 is a top view thereof;

FIG. 12 is a bottom view thereof;

FIG. 13 is a rear view thereof; and

FIG. 14 is a front view thereof.

FIG. 15 is a perspective view of a collapsed handle showing our new design and having the fork tines folded back;

FIG. 16 is a right side view thereof;

FIG. 17 is left side view thereof;

FIG. 18 is a top view thereof;

FIG. 19 is a bottom view thereof;

FIG. 20 is a rear view thereof; and,

FIG. 21 is a front view thereof.

The broken lines shown in the drawings are for illustrative purposes only and form no part of the claimed design.
